COMBINED SCORER AND PEELER FOR
CITRUS FRUITS

Peter J. Perry, 1900 18th Ave. S.,
Seattle, Wash. 98144

Filed Feb. 1, 1967, Ser. No. 5,647

Term of patent 14 years

(Cl. D89—1)

FIG. 1

FIG. 2

FIG. 3

FIGURE 1 is a plan view of one side of a combined scorer and peeler for citrus fruits showing my new design.

FIG. 2 is a front edge elevational view;

FIG. 3 is a bottom plan view; and

FIG. 4 is a sectional view taken on line 4—4 of FIG. 1.

I claim:

The ornamental design for a combined scorer and peeler for citrus fruits, substantially as shown.
